HYDROCARBON CONVERSION

James M. Jennings, Baton Rouge, La., and George F. Pappas, Metuchen, N. J., assignors to Standard Oil Development Company, a corporation of Delaware

Application May 1, 1951, Serial No. 223,938

5 Claims. (Cl. 196—49)

1

The present invention relates to a process for the thermal conversion of hydrocarbonaceous materials. More particularly the invention pertains to an improved method of reducing the viscosity of heavy hydrocarbonaceous residues of the type of topped or reduced crude or similar materials by a thermal treatment suitable to produce fuel oils of improved quality, gas oils and increased proportions of motor fuel range hydrocarbons. Broadly, the invention provides for subjecting heavy residues of the type specified to a viscosity-reducing or "visbreaking" treatment at severe conditions suitable for the production of higher yields of gasoline and re-visbreaking the high-severity visbreaker tar in a second visbreaking stage at relatively mild conditions conducive to the production of high quality fuel oil.

In refining crude oil the first step is normally a simple distillation or "topping" to produce distillate fractions and a heavy residue. In order to obtain maximum yields of high quality motor fuels, all fractions boiling above the gasoline range and particularly those boiling above the heating oil range must be subjected to catalytic cracking. However, the heavy residuum of conventional crude distillation boiling above about 800° F. does not, as such represent a feed stock suitable for catalytic cracking. Among the methods developed to produce satisfactory catalytic cracking feed stocks from these residues, viscosity reduction or "visbreaking" is one of the most widely used.

Visbreaking involves a treatment of reduced crude or the like at temperatures of about 780-950° F. and pressures of about 100-1500 p. s. i. g. at feed rates of 1-75 volumes per hour of oil at 60° F. per cracking volume above 750° F. to produce by a mild type of thermal cracking about 5-15 vol. per cent of gas oil, about 5-15 vol. per cent of gasoline and about 90-70 vol. per cent of heavy fuel oil. Specific conditions within the ranges specified depend on the type of the visbreaker feed. The gas oil so formed represents a feed stock suitable for the production of additional amounts of high quality gasoline by catalytic cracking or, after suitable finishing, an acceptable distillate fuel. Of the products formed in visbreaking, the gasoline has the highest and the fuel oil the lowest value. In order to obtain the greatest product realization it is highly desirable, therefore, to reduce the fuel oil yields to a minimum while simultaneously increasing the gasoline and gas oil yields to a maximum. This may be accomplished by increasing the

severity of the thermal cracking treatment, that is, by raising the temperature and/or extending the cracking time. However, when so operating the quality of the product fuel oil, particularly its sedimentation characteristics are impaired to an extent which makes the fuel oil unacceptable for most purposes. Therefore, a visbreaking operation permitting the production of increased yields of gasoline and gas oil and simultaneously 10 of fuel oil in smaller amounts but of satisfactory sediment characteristics, has become a need strongly felt in the art of petroleum refining. The present invention provides an operation of this type.

15 It is, therefore, the principal object of this invention to provide improved means for vis-breaking heavy petroleum residues of the type specified, permitting the production of maximum yields of motor and distillate fuels and relatively small yields of a high quality heavy fuel oil. Other objects and advantages will appear from the subsequent description of the invention wherein reference will be made to the accompanying drawing, the single figure of which is 20 a schematical flow diagram of a system suitable to carry out an embodiment of the invention.

25 It has now been found that the yields of low boiling distillates such as gas oils and gasoline may be substantially increased over conventional visbreaking at relatively mild conditions, without detrimentally affecting the quality of the fuel oil product, by subjecting the heavy vis-breaking feed stock first to a visbreaking treatment carried out at severe conditions conducive to the formation of increased proportions of 30 lower boiling distillate oils and thereafter re-visbreaking the visbreaker tar from the severe visbreaking treatment in a second visbreaking stage at conventional conditions, which are comparatively mild. The pitch feed to the second visbreaking stage is preferably asphaltic or virgin asphalt is preferably added to this pitch in amounts of 2-12%, in order further to improve the quality of the fuel oil produced.

35 40 45 First stage severe visbreaking conditions include temperatures of about 850-975° F., preferably about 920-960° F., pressures of about 200-1100 p. s. i. g., preferably about 300-1000 p. s. i. g. and oil residence times at visbreaking conditions, corresponding to about 15 to 50 volumes 50 per hour of oil at 60° F. per first stage visbreaker volume above 750° F. Specific conditions vary with the type of visbreaker feed. However, the conditions to be applied in this stage should be more severe, within the ranges specified, than

2

the more conventional conditions employed in the second stage. Particularly, the temperature should be about 50-100° F. higher than the conventional temperatures of the second stage. Similar results may be accomplished by increasing residence time, by, say, about 50-200%. By way of example, conventional visbreaking conditions to be maintained in the second stage may include temperatures of about 700-900° F., preferably about 780-900° F., pressures of about 200-1000 p. s. i. g., preferably about 500 to 1000 p. s. i. g., and residence times when using coil and upflow or downflow soakers corresponding to about 2.5 to 30 volumes per hour of oil at 60° F. per second stage visbreaker volume above 15 10 750° F. (v./v./hr.) or 10-30 v./v./hr. when using only a visbreaker coil.

All types of conventional visbreaking systems such as coil only, tube-and-tank type arrangements, suspensoid, fluid or moving bed type of operations may be readily adapted to the present invention. In accordance with a preferred embodiment of the invention, a tar-containing portion or all of the liquid product from the severe visbreaking stage is retreated in a visbreaking 25 zone wherein fresh visbreaker feed is simultaneously visbroken at conventional mild conditions.

The beneficial effects of the process of the invention are demonstrated by the data reported below which were obtained in commercial visbreaking operations. Two visbreaking units A and B were operated in parallel. Unit A was a conventional tube-and-tank type system in which a 13-15° API mixture of vacuum reduced asphaltic and paraffinic reduced crude, gas-oil-fluxed asphalt from a propane deasphalting operation and bottoms from a slop rerunning operation was heated in furnace coils to about 840° to 850° F., at a feed rate of about 16,000 bbl./day and at a pressure of about 300 to 1,000 p. s. i. g. at about 15 v./v./hr. above 750° F. The feed so heated was discharged into a downflow soaking drum maintaining no appreciable liquid level, or an incremental residence time therein, substantially at the conditions of the visbreaker coil. The visbroken product was passed from the soaking drum to a separator maintained at about 720 to 760° F. and about 25 to 35 p. s. i. g. pressure. Separator overhead was fractionated in a product fractionator while separator bottoms were flashed into a flash drum to atmospheric pressure and at temperatures of about 500 to 600° F. The flash drum overhead was recovered together with the separator overhead while the flash drum bottoms were recovered as fuel oil stock, all in a substantially conventional manner.

Unit B was a coil only system in which the feed consisting of 10-12° API mixture of vacuum reduced South Louisiana and Louisiana-Mississippi crudes was heated in a furnace coil of semi-commercial scale to about 940 to 955° F. at a pressure of 700 to 750 p. s. i. g. and a throughput of about 24-29 v./v./hr. to obtain high severity visbreaking. The visbroken product was directly passed to a separator maintained at about 350 to 450° F. and about 100 to 125 p. s. i. g. pressure. The liquid product from the separator was fluxed with 30% light catalytic gas oil and flashed in the flash drum of unit A, so that the fuel oil stock recovered from this joint flash drum represented a mixture of tars produced at conventional mild and high severity conditions. This stock was blended with light catalytic gas oil and tested for its sediment characteristics by a standard filtration procedure in which sediment 5 10 15 20 25 30 35 40 45 50 55 60 65 70 75

is reported in wt. per cent, sediments in excess of 0.25 wt. per cent being considered unsatisfactory. In previous operations the sediment of tar produced in unit A alone had been found to be satisfactory and never exceeded 0.25 wt. per cent.

In the combined operation described it was found impossible to blend appreciable proportions of the high severity tar from unit B with the satisfactory low severity tar from unit A without producing blends exceeding the maximum permissible sedimentation limit. This is illustrated by the tar inspection data summarized in Table I below:

Table I

Run No.	I	II	III
Tar Production Rate, Unit A, Bbl./day.	13,000-14,000	13,000-14,000	13,000-14,000
Tar Production Rate, Unit B, Bbl./day.	100.....	100+.....	50
Sediment of Combined Tars, Wt. Percent.	Too High.....	Too High.....	0.13

The data of Table I show that even blends containing as little as 100 bbl. of high severity tar per 13,000-14,000 bbl. of satisfactory tar, i. e., less than 1%, exceed permissible sediment limits.

Following the operation reported above the liquid product from the separator of high severity unit B was fed to the furnace coil of unit A together with the regular feed of unit A. Summarized results of this operation are given in Table II below:

Table II

Run No.	I	II
Conditions—Feed Rates to Unit:		
Regular Feed, Bbl./day.....	13,000	13,000.
Liquid Product from Unit B, Bbl./day.....	1,500	2,500.
Total Feed Rate, Bbl./day.....	14,500	15,500.
Coil Outlet Temperature, ° F.....	820-850	820-850.
Pressure, p. s. i. g.	400	400.
Flash Drum Tar, Bbl./day (Estimate).	13,000-14,000	13,000-14,000.
Flash Drum Tar Inspection: Sediment, Wt. Percent.	0.11	Met Specification.

The data of Table II demonstrate that when operating in accordance with the present invention a visbreaker tar having satisfactory sedimentation characteristics may be produced from a feed about 15-25% of which is visbroken at high severity conditions conducive to increased yields of lower boiling distillates. Comparison of these results with those reported in Table I proves the significant advantages of the process of the invention with respect to the sediment characteristics of the fuel oil which may be produced in high severity visbreaking operations. The considerable increase in the severity tolerance of the visbreaking process thus afforded also permits a corresponding increase in total visbreaker conversion and distillate yields without detriment with respect to fuel oil quality. While the coil outlet temperature in the second stage of runs I and II was at times lower than that specified above for conventional operation, subsequent operations indicate that no such temperature reduction is required in the second stage.

Having set forth its objects and general nature, the invention will be further explained by the following description of the system shown in the drawing which illustrates a preferred mode of practicing the invention.

Referring now in detail to the drawing, the

system illustrated therein essentially comprises a conventional type low-severity visbreaking unit A and a high-severity type visbreaking unit B the functions and cooperation of which will be forthwith explained.

In operation, a virgin crude distillation residuum such as a vacuum distillation residue boiling above about 800° F. may be supplied from line 1 by feed pump 3 via line 5 to visbreaking coil 7. This feed stock is preferably an asphaltic pitch or contains virgin asphalt. The oil supplied from line 1 may have the temperature at which it is recovered from the crude still, say, about 500-750° F. In line 5, the virgin oil feed is mixed with about 15 to 20% of liquid high-severity visbreaker product obtained as will appear hereinafter and supplied from line 9 at a temperature of about 300 to 400° F. The mixed feed enters low severity visbreaking coil 7 at a pressure of about 700 to 750 p. s. i. g. and is heated therein to about 820 to 860° F. within a residence time of about 2 to 5 minutes. The effluent from coil 7 is passed through line 11 to downflow or upflow soaker 13 wherein it may be maintained substantially at the temperature and pressure of coil 7 for an additional say 1-15 minutes depending on the soaker type, to complete the visbreaking reaction. The visbroken product is withdrawn from soaker 13 through line 15 provided with pressure release valve 17 and passed to a vapor-liquid separator 19 maintained at a pressure of about 30 to 35 p. s. i. g. and a temperature of about 720 to 760° F. Vapors separated in separator 19 leaving via line 21, are fed to a conventional product fractionator 25. Distillate fractions may be recovered from fractionator 25 in any desired manner as exemplified by lines 27, 29 and 31. Bottoms are withdrawn via line 33 and can be recovered wholly or in part through line 35 for reprocessing in other operations or may be returned to low severity coil 7 via line 36 with the fresh feed.

Returning now to separator 19, the separated liquid product is withdrawn through line 37 provided with pressure release valve 39 and flashed at atmospheric pressure into flash drum 41. Flash drum 41 may be maintained at a temperature of about 500° to 600° F. Stripping steam may be injected through lines 42. A distillate vapor fraction boiling below about 800° to 850° F. may be removed via line 43 to be further treated in any conventional manner. The bottoms of flash drum 41 are recovered through line 45 as product tar complying with fuel oil specifications.

A second residual feed stock which may be the same as, or different from, that supplied via line 1 is fed from line 47, preferably at its production temperature, by feed pump 49 to high severity visbreaking coil 51 which it may enter at a pressure of about 700 to 800 p. s. i. g. Coil 51 may be maintained at an outlet temperature of about 900° to 975° F. and provide for an oil residence time of about 1 to 4 minutes to complete the visbreaking reaction. The visbroken product is withdrawn via line 53 and may be passed through lines 55 and 57 provided with pressure release valve 59 to vapor-liquid separator 61 which may be maintained at a pressure of about 0 to 150 p. s. i. g. and a temperature of about 350° to 450° F. Overhead vapors from separator 61 are withdrawn through line 63 provided with release valve 65 and may be passed to product fractionator 25 to be treated therein together with the overhead from separator 19 as described above. The liquid products separated in separator 61 are with-

drawn through line 67 and supplied by pump 69 to line 9 to be combined in line 5 with the virgin feed to coil 7 as described above.

When operating substantially as described above, the gasoline and gas oil yields obtained from the total oil feed to Sections A and B are substantially higher than those obtained by processing of the same amount of feed in a system of the type of section A alone. The increase in gasoline yield amounts to about 20 to 70% and the increase in gas oil yield to about 10 to 60% based on conventional yields. The amount of fuel oil produced in the case of two stage processing is about 3 to 8% less on the same basis than that obtainable in single stage processing in section A; however, fuel oil quality is equally satisfactory in both cases. When the total feed of sections A and B is processed in a system of the type of section B alone, the amounts of gasoline and gas oil produced are higher, and the amount of fuel oil produced lower than in the case of processing as described with reference to the drawing. However, the fuel oil produced by all-high-severity processing is not a saleable product.

The operation described with reference to the drawing permits of various modifications without a significant change in the contemplated results. For example, soaker 71 may be used in high severity cracking section B providing for a larger oil residence time substantially at the temperature and pressure of coil 51. In this case, the residence time in coil 51 may be substantially reduced and its effluent passed through line 55 to soaker 71. The soaked product is withdrawn through line 73 and may be passed directly to line 9 and from there to line 5 and coil 7. All or any desired portion of the effluent of soaker 71 may be passed via line 75 provided with release valve 77 to separator 61 and treated therein substantially as described above with reference to separator 61. Rather than passing the total effluent of coil 51 to soaker 71 it may be fed from line 53 via line 79 to lines 9 and 5 and coil 7. If desired, soaker 13 of section A may be by-passed by the effluent of coil 7 via line 81, in which case the residence time in coil 7 will be correspondingly increased to make up for the residence time of the by-passed soaker. In all modifications, except in the case in which soaker 13 is by-passed by line 81, the high-severity visbreaker product flowing through line 9 may be added via lines 83 and 11 directly to soaker 13 to be subjected therein to the mild conditions of visbreaking section A. In place of, or in addition to, the virgin oil feed supplied through line 1, an asphalt material such as asphalt-containing pitch or extraneous virgin asphalt in proportions of about 2 to 12 wt. percent based on the material in line 9, may be supplied through line 85 to be mixed with high severity visbreaker product in line 9. The addition of such materials through line 85 is particularly desirable in cases in which a feed stock of relatively low asphalt content is supplied via line 1. Either one or both of the visbreaker coils 7 and 51 may have the form of double coils operated in parallel, in a manner known as such. Other modifications within the spirit of the invention may appear to those skilled in the art.

The above description and exemplary operations have served to illustrate specific embodiments of the invention but are not intended to be limiting in scope.

What is claimed is:

1. In the process of producing distillate oils

and high quality residual fuel oils of low-sediment content by visbreaking heavy virgin crude distillation residues, the improvement which comprises passing a feed stream consisting essentially of a virgin distillation residue boiling essentially above 800° F. through a visbreaking zone under relatively severe conditions including a reaction temperature of 850 to 975° F., separating the resulting hydrocarbon product into a vapor fraction and a first-stage residual tar fraction, mixing at least a portion of the separated tar fraction with another feed stream of a distillation residue of an asphalt-containing virgin crude stock boiling essentially above 800° F. to give a mixture containing about 15 to 20 parts of the tar fraction per 100 parts of the virgin stock, passing the mixture through a second visbreaking zone under relatively mild conditions including a reaction temperature of about 750 to 900° F. and a residence time corresponding to about 2.5 to 30 v./v./hr. above 750° F., the reaction temperature in said second visbreaking zone being about 50 to 100° F. lower than the temperature in said first visbreaking zone, separating the resulting hydrocarbon mixture into a vapor fraction and a low-sediment residual tar fraction, and recovering the low-sediment tar.

2. A process according to claim 1 wherein the mixture fed to the mild second visbreaking zone contains about 2 to 12% of virgin asphalt based on the tar fraction present in the mixture.

3. A process according to claim 1 wherein the residence time in the severe first visbreaking zone is 50 to 200% longer than the residence time in the mild second visbreaking zone.

4. A process according to claim 1 wherein the virgin residue fed to both visbreaking zones is a vacuum reduced crude, about 15 to 25% of this reduced crude being introduced directly to the severe first visbreaking zone while the balance of the reduced crude is introduced directly to the mild second visbreaking zone.

5. In the process of producing distillate oils and high quality residual fuel oil by visbreaking crude distillation residues, the improvement which comprises passing a feed stream consisting essentially of a virgin crude distillation residue boiling essentially above 800° F. through a visbreaking zone under relatively severe conditions including a reaction temperature of 920 to 960° F., a pressure of about 700 to 800 p. s. i. g. and an oil residence time of about 1 to 4 minutes, separating the resulting hydrocarbon product into a vapor fraction and a first-stage residual tar fraction, mixing the separated tar fraction with another feed stream of a distillation residue of an asphaltic virgin crude boiling essentially above 800° F. to give a mixture containing about 15 to 20 parts of the tar fraction per 100 parts of the virgin stock, passing the mixture through a second visbreaking zone under relatively mild conditions including a reaction temperature of about 820 to 900° F., a pressure of about 300 to 1000 p. s. i. g. and an oil residence time corresponding to about 2.5 to 30 v./v./hr. above 750° F., the reaction temperature in said second visbreaking zone being about 50 to 100° F. lower than the temperature in said first visbreaking zone, separating the resulting hydrocarbon mixture into a vapor fraction and a second-stage residual tar fraction, and recovering the said second-stage tar.
